DELIVERY MECHANISM FOR PRINTING-MACHINES.

1,342,187.

specification of Letters Patent.

Patented June 1, 1920.

Application filed August 6, 1918, Serial No. 248,519. Renewed April 23, 1920. Serial No. 376,175.

To all whom it may concern:

Be it known that I, AMOS H. SMITH, a citizen of the United States, residing at the borough of Brooklyn, city of New York, county of Kings, and State of New York, have invented certain new and useful Improvements in Delivery Mechanisms for Printing-Machines, of which the following is a specification, reference being had therein 10 to the accompanying drawings, which form a part thereof.

My invention relates to delivery mechanisms for printing machines, and more particularly to a mechanism particularly adapted for use upon rotary plate machines.

In plate printing machines of the rotary type, the imprint is made upon damped sheets of paper, which are pressed, with considerable force, against the plate by the 20 impression cylinder, so that the grippers of the delivery mechanism to remove the sheet, must be inserted between the paper and the plate in order to pick up the forward edge of the paper, without crumpling or mutilating same.

There has heretofore been devised a gripper mechanism for delivering the sheets from the plate, embodying therein means for lifting the forward edge of the sheet from the 30 plate, so as to facilitate the entry of the grippers between this edge and the plate, but this mechanism necessitated the use of movable members carried by the plate cylinder which had to be coördinated in their 35 functions with the gripper mechanism, requiring great nicety in the adjustment of the various parts.

In a delivery mechanism, a sequence of grippers are used, and in such mechanisms 40 heretofore employed, it has always been necessary to adjust each of the gripper fingers with relation to each particular plate mounted upon the cylinder, no means being provided for compensating for irregularities in 45 the plate, or permitting a variable, or differential actuation of the different gripper fingers, to conform to variations in different portions of the plate.

In a delivery mechanism made in accordance with my invention, the gripper fingers are so constructed as to not only readily pass under, and lift the sheet from the plate, but to automatically adjust themselves to irregularities in the surface of the plate, in a man-

ner to insure all of the fingers passing beneath the forward edge of the sheet. In this manner all of the gripper fingers may be simultaneously actuated by means of an oscillatory shaft, common to all of said fingers, the degree of oscillation of this shaft being constant, but the different fingers upon said shaft being capable of a variable movement as to the portion thereof engaging the plate, irrespective of this constant movement of the actuating shaft.

While the rotary speed of the grippers must be so proportioned to the speed of movement of the plate, as to insure the accurate presentation of said grippers to the forward edge of each sheet as it is to be delivered, I so construct this mechanism as to cause a variable movement of the plate and the grippers while the latter are operative to lift the edge of the sheet from the plate, so as to cause a sufficient advance of the sheet 75 with relation to the gripper fingers, to insure the engagement of the sheet between said fingers and the gripping areas coöperating therewith, the movement of said gripper fingers being accelerated during some portion of each revolution thereof, to compensate for the retardation incidental to the feeding movement of the paper in relation to said fingers, and insure accuracy in the timing of the movement of the gripper 80 mechanism with relation to the plate during the delivery of succeeding sheets.

A delivery mechanism made in accordance with my invention is so constructed as to avoid undue wear of the plate by reason of 90 the repeated engagement of the fingers therewith.

The invention consists primarily in a delivery mechanism for printing machines, embodying therein a rotatable member having a plurality of gripping areas thereon, means actuating said member, a plurality of gripper fingers coöperating with said gripping areas respectively, said gripper fingers each embodying therein means whereby, 95 with the actuation thereof, each finger will be yieldingly thrust into engagement with the printing plate, and means adapted to impart a timely and simultaneous actuation to said fingers to insure the engagement and 100 disengagement of the fingers with the paper; and in such other novel features of construction and combination of parts, as are

hereinafter set forth and described, and more particularly pointed out in the claims hereto appended.

Referring to the drawings,

5 Figure 1 is a section through a delivery cylinder embodying my invention, the gripper fingers being shown in the opened position in relation to a printing plate;

10 Fig. 2 is a similar view showing the grippers closed upon a sheet;

15 Fig. 3 is a side view of the means for imparting a variable rotary movement to the gripper fingers; and

20 Fig. 4 is a section on line 4—4 of Fig. 3.

25 Like letters refer to like parts throughout the several views.

I have referred to the delivery mechanism as being adapted for use with a rotary plate machine, and have so shown it in the drawings, since this mechanism is particularly adapted to be used with this type of machine. The mechanism may be used, however, with flat bed machines with merely those modifications incidental to the change 25 in the design of the machine.

30 In the embodiment of my invention shown in the drawings, *a* indicates the plate cylinder of a rotary machine, having a plate *a'* thereon. Associated with said cylinder, beyond the impression cylinder, which is not shown in the drawings, is a shaft *b* having mounted thereon a sequence of rings or wheels *c*, about which the usual tapes *c'* pass, said tapes having associated therewith the parallel tapes *c²*. The tape arrangement is old and well known in this art, no claim of invention being made thereto.

35 Carried by some, or all, of the rings or 40 wheels *c* are gripper fingers each adapted to coöperate with a gripping area *c³* upon the ring carrying same, these gripper fingers receiving timely actuations to insure their engagement with the forward edge 45 of the sheet, after it has passed the impression cylinder, and to release the sheet as it is delivered to the tapes *c'* and *c²*. While any desired mechanism for thus actuating said gripper fingers, may be employed, I 50 prefer to mount all of said fingers upon a shaft *d* mounted adjacent the periphery of the rings or wheels *c*, and receiving movement therefrom. This shaft may be rocked to open and close the fingers by 55 any desired mechanism, such as the cam *d'* acting upon the crank arm *d²* carried by said shaft. The cam *d'* has a rise and fall *d³* adapted to open and close the grippers when picking up the sheet from the plate, 60 and a second rise and fall *d⁴* adapted to open the grippers, to accomplish the delivery of the sheet to the tapes *c'* and *c²*, and subsequently close them. By this construction, I insure the simultaneous actuation 65 of all of the gripper fingers to the

same extent, which is an essential characteristic of the delivery mechanism. Any actuating mechanism which may secure the desired effect, could be used, however, in lieu of that shown in the drawings.

70

The various rings or wheels *c* may be, and preferably are, adjustably mounted upon the shaft *b*, to permit the adjustment of the delivery mechanism for use with sheets of different sizes, and to permit 75 peripheral adjustment of the grippers to secure accuracy in the delivery of the sheets.

80 Each of the grippers is identical in structure with every other, so that a detailed description of but one of them is essential to an understanding of the present invention. These grippers are so constructed as to receive a positive opening and closing movement with the oscillation of the shaft *d*, and yet have the portion thereof 85 engaging the plate, capable of such movement independently of said shaft, as to permit this portion to be brought yielding in contact with the plate, thus insuring 90 the desired intimate relation thereof with the plate to prevent the edge of the sheet butting against the edge of this portion of the finger with a resultant crumpling or mutilation of the sheet. By this 95 construction a slight overthrow of the shaft *d* can be provided for, the yielding contact of the gripper finger with the plate resulting in this finger adjusting itself to the plate, and not only causing it to follow 100 any slight irregularities in the plate adjacent the forward edge of the sheet, but causing all of the fingers to positively bear upon the plate and thus assume the same relation thereto. This avoids the necessity 105 for extreme nicety in the adjustment of the several fingers.

110 Each finger comprises a block *e* adjustably mounted upon the shaft *d*, as by means of the split hub *e'*. The block *e* is mounted adjacent the wheel or ring *c* and is provided with a stop *e²*, and an offset spring seat *e³* upon opposite sides of the shaft *d*. The block *e* is secured to the shaft *d* so as to have movement therewith.

115 Pivotedly mounted in relation to the block *e*, is a gripper portion *f* so shaped as to conform to the curvature of the ring or wheel *c* and so positioned as to coöperate with the gripping area *c³* thereon. The 120 portion *f* is provided with a heel *f'*, co-operating with the stop *e²*, and a spring seat *f²* oppositely disposed as to the spring seat *e³*. A spring *g* acts between the opposed spring seats *f²* and *e³*, being so tensioned as to normally hold the heel *f'* in contact with the stop *e²*. By this construction the gripper portions *e* and *f* are adapted to have simultaneous movement in both directions, the portion *f* however, be- 130

ing adapted to have movement independently of the portion *e* in one direction, so as to permit said portion *f* to be brought yieldingly in contact with the plate.

5 Supported by, and projecting forwardly of, the gripper *f* is a resilient lifting tongue *h*, the forward end of which is curved slightly downwardly, or toward the plate when the gripper fingers are in the operative relation thereto, the contact end of said tongue being normally positioned below the lower face of the portion *f* and the curvature thereof being such as to position the paper between the portion *f* and 10 the opposed gripping area *c*³. I preferably make the tongue *h* of flat spring stock, curving the forward edge thereof so as to have a substantial lineal contact thereof with the plate, while insuring a substantial 15 area of contact between said tongue and the sheet. The flexibility of the tongue *h* supplements the action of the spring *g* in securing a yielding contact between the gripper portion *f* and the plate, the association of the portion *f* and the tongue *h* 20 permitting the desired intimacy in the contact of these parts with the plate, with a light pressure thereof upon the plate, in a manner to minimize likelihood of wear 25 of the plate as a result of the repeated engagement of these parts therewith.

Ordinarily when the gripper mechanism picks up the sheet from the plate, the printing couple is still making a portion of the 30 imprint upon the sheet, so that it is essential that until the sheet is released by the gripper mechanism, the peripheral speed of the rings or wheels *c* shall coincide with the speed of traverse of the printing couple. 35 Since, however, the grippers, in delivering the sheet, move in the same direction as the sheet, it is essential that as the portions *f* and *h* engage the plate, the movement thereof be either retarded or reversed motionarily, or until the paper has been positioned between the portion *f* and the co-operating gripping area *c*³.

To secure this result, I provide actuating means for the shaft *b*, which, by insuring 40 the desired synchronism between the delivery mechanism and the printing couple, will nevertheless vary the speed of rotation of the shaft *b*, first to insure the proper picking up of the sheet, and second to compensate for the retardation incidental thereto by an accelerated speed of rotation during a portion of each revolution, subsequent to such retardation.

The actuating means for the shaft *b* comprises a gear *i* entrained with a gear upon 45 the printing couple, or driven at the desired speed in any desired manner. This gear carries a stud *i'* upon which is mounted a bell crank lever *j*. One arm of this lever

b' keyed, or otherwise secured, to the shaft *b*. The other arm of the lever *j* carries a roller *j'* seated in the groove of a housed cam *m*, said cam being non-rotary and having a rise *m'* at one point thereof coinciding with the interval of the engagement of the gripper fingers with the plate, and a fall *m*² coinciding with the interval subsequent to the disengagement of said fingers from the sheet. The portions of the cam 70 grooved between said rise and said fall, and between said fall and said rise, are concentric with the axis of the shaft *b*. The height of the rise *m'* is identical with the depth of the fall *m*², so that the direct and 75 return oscillation of the lever *j* will be the same. By this construction the gear *i* may rotate at uniform speed, applying its power to the shaft *b* through a mechanism, to wit:—the lever *j* and the link *k*, which is 80 capable, through a suitable controlling mechanism, to vary the speed of rotation of said shaft, independently of said gear.

I have shown in the drawings, and have herein described, only those portions of the 90 printing machine incidental to an understanding of the mode of operation of the delivery mechanism, the details of construction of other mechanisms being immaterial to the present invention.

The operation of the herein described delivery mechanism is substantially as follows:—

While a machine is in operation, the rings or wheels *c* will rotate in synchronism with 100 the actuation of the printing couple, the number of rotations of said rings or wheels, with each cycle of the printing couple, being capable of variation as determined by the number of plates *a'* upon the plate cylinder *a*. As the gear *i* rotates, the stud *i'* thereon will carry the bell crank lever *j* about with it, said lever normally having no oscillatory movement upon said stud, since any such movement of said lever is controlled by the cam *m*.

While the lever *j'* is thus traveling without oscillatory movement, the link *k* will, through the crank arm *b'*, rotate the shaft *b* at the same speed as that of the gear *i*.

As the various gripper fingers and the forward edge of a plate *a'* converge toward each other, one of the rises, *d*³, upon the cam *d'* will oscillate the shaft *d* in a manner to open all of the grippers, thrusting 115 said grippers toward the plate and into the desired close contact therewith. The movement of said shaft causes similar movement of the blocks *e*, and through the springs *g* of the portions *f* of the several grippers. By 120 so forming the rise *d*³ as to impart a slight overthrow of the shaft *d*, the portion *f* of each gripper will be brought into positive contact with the surface of the plate, the spring *g* of each gripper yielding after such 130

contact to permit the portion f to adjust itself to the surface of the plate. Thus, if any gripper is not so set as to bear properly upon the plate, or if there be a high, or a low, spot on the plate at the point of contact of the gripper therewith, the independent movement of the portion f will compensate for this irregularity, and all grippers of the sequence will bear directly upon the plate. Possibility of the paper passing beneath, or butting against, the edge of this portion, is thus avoided. At the same time, the resiliency of the tongue h will permit this tongue to yield slightly upon contact with the plate, the portion intermediate the end thereof, and the end of the portion f being thrust slightly above said portion f , so as to guide the sheet between said portion f and the opposed gripper area c^3 .

When the grippers are in the position above referred to, the rise m' of the cam m , becomes operative upon the lever j , to oscillate it upon the stud i' . This oscillatory movement will impart a thrust to the link h in a direction opposite to that of the direction of rotation of the shaft b and the stud i' , thus causing a retardation, dwell or backward thrust as to the shaft b , through the crank arm b' . The exact operative effect of this mechanism upon the shaft b will be determined by the angle of the rise m' , the duration of this operation being controlled by the length of this rise. While said lever is being oscillated, the sheet will have a feeding movement in relation to the grippers. As the roller j' reaches the top of the rise m' , the oscillatory movement of the lever j ceases, and so long as the cam groove remains concentric with the shaft b , the speed of rotation of said shaft will be the same as that of the gear i , which speed will be coincident with the rate of travel of the plate. While the mechanism for retarding the shaft b is operative, or immediately thereafter, the cam d' actuates the shaft d to close the grippers upon the sheet, the sheet thus being transferred, as it is printed, from the plate a' to the collecting mechanism.

As the grippers approach the tapes c' and c^2 , and immediately after the sheet passes between said tapes, the rise d^4 upon said cam, opens the grippers, and thereafter the travel of the sheet results from that of the said tapes.

After the sheet has been completely printed, and while it is being conveyed by the tapes c' and c^2 , the movement of the shaft b is accelerated to compensate for the retardation period, this acceleration resulting from the action of the fall m^2 upon the lever j . As the roller j' is acted upon by this fall, the lever j is oscillated in the opposite direction, or returned to normal. This movement of the lever j will exert a pull upon

the crank arm b' through the link h , this movement being in the direction of rotation of the gear i , thus accelerating the speed of rotation of said shaft b . The depth of the fall m^2 being the same as the height of the rise m' , the degree of acceleration will correspond with the degree of retardation, thus preserving the relation in the cycle of operations of the delivery mechanism, and that of the printing couple. After leaving the fall m^2 , the speed of rotation of the shaft b will be the same as that of the gear i .

The mechanism for imparting variable speed of rotation of the shaft b , it will be observed, is positive, thus insuring accuracy in the timing of these operations. Furthermore, the mechanism is such as to permit variance in the adjustment of the different gripper wheels without affecting the adjustments of this mechanism, which are constant.

It is not my intention to limit the invention to the precise details of construction shown in the accompanying drawings, it being apparent that such may be varied while yet securing the desired yielding contact of the grippers with the plate, to insure all of the grippers being pressed against the plate in a manner to cause them to conform to the plate and pass beneath the paper. Furthermore, other means than that shown and described, may be employed for insuring that retardation, dwell, or backward thrust of the grippers, for the purpose of permitting a feeding movement of the paper in relation to the grippers, without departing from the spirit and scope of the invention.

Having described the invention, what I claim as new and desire to have protected by Letters Patent, is:—

1. A delivery mechanism for printing machines, embodying therein a rotatable member having a plurality of gripping areas thereon associated with the plate cylinder, means actuating said member, a plurality of gripper fingers co-operating with said gripping areas respectively, said gripper fingers each embodying therein means whereby, with the actuation thereof, each finger will be yieldingly thrust into engagement with the printing plate, means adapted to impart a timely and simultaneous actuation to said fingers first into engagement with the plate, and then into engagement with said gripping areas, and subsequently away from said areas to insure the engagement and disengagement thereof with the paper and means varying the relative peripheral speed of said fingers and the plate while said fingers are in engagement therewith.

2. A delivery mechanism for printing machines, embodying therein a rotatable member having a plurality of gripping areas thereon associated with the plate cylinder, a plurality of gripper fingers co-operating

- with said gripping areas respectively, said gripper fingers each embodying therein means whereby, with the actuation thereof, each finger will be yieldingly thrust into engagement with the printing plate, means adapted to impart a timely and simultaneous actuation to said fingers to insure the engagement and disengagement thereof with the paper, and an actuating mechanism for 5 engagement with the printing plate, means adapted to impart a timely and simultaneous actuation to said fingers to insure the engagement and disengagement thereof with the paper, and an actuating mechanism for 10 said rotatable member, embodying therein means whereby, during each rotation thereof, the rotary movement of said member will be controlled to permit a feeding movement of the paper in relation to said fingers 15 while they are in engagement with the plate, and will be accelerated to preserve the operative relation of said fingers to said plate, as to the succeeding delivery operation.
- 20 3. A delivery mechanism for printing machines, embodying therein a rotatable member having a plurality of gripping areas thereon associated with the plate cylinder, means actuating said member, an oscillatory shaft carried by, and rotatable with, said rotatable member, a plurality of gripper fingers mounted upon said shaft, and co-operating with said gripping areas respectively, said gripper fingers each embodying therein 25 means whereby, with the actuation thereof, each finger will be yieldingly thrust into engagement with the printing plate, means adapted to impart a timely actuation to said shaft to first thrust said fingers into engagement with the plate, and then into engagement with said gripping areas, and subsequently away from said areas to insure the engagement and disengagement of said fingers with the paper and means varying the 30 relative peripheral speed of said fingers and the plate while said fingers are in engagement therewith.
- 40 4. A delivery mechanism for printing machines, embodying therein a rotatable member having a plurality of gripping areas thereon associated with the plate cylinder, means actuating said member, an oscillatory shaft carried by, and rotatable with, said rotatable member, a plurality of gripper fingers mounted upon said shaft, and co-operating with said gripping areas respectively, said gripper fingers each embodying therein a block carried by, and movable with, said shaft, a gripping portion pivotally mounted in relation to said block, cooperating means carried by said block and said gripping portion respectively, whereby said gripping portion and said block are moved in unison in one direction, and a 45 flexible connection adapted to transmit movement from said block to said portion in the other direction, whereby, with the actuation thereof, each finger will be yieldingly thrust into engagement with the printing plate, means adapted to impart a 50
- timely actuation to said shaft to first thrust said gripping portions into engagement with the plate and then into engagement with said gripping areas, and subsequently away from said areas to insure the engagement and disengagement of said fingers with the paper and means varying the relative peripheral speed of said fingers and the plate while said gripping portions are in engagement therewith. 55
- 60 5. A delivery mechanism for printing machines, embodying therein a rotatable member having a plurality of gripping areas thereon associated with the plate cylinder, means actuating said member, an oscillatory shaft carried by, and rotatable with, said rotatable member, a plurality of gripper fingers mounted upon said shaft, and co-operating with said gripping areas respectively, said gripper fingers each embodying therein a block carried by, and movable with, said shaft, having a stop upon one side of said shaft, and a spring seat upon the opposite side thereof, a portion pivotally mounted in relation to said block, having a heel adapted to co-operate with said stop and a spring seat oppositely disposed to the spring seat upon said block, and a spring mounted between said spring seats, whereby, with the actuation thereof, each finger will be yieldingly thrust into engagement with the printing plate, means adapted to impart a timely actuation to said shaft to first thrust said gripping portions into engagement with the plate and then into engagement with said gripping areas, and subsequently away from said areas to insure the engagement and disengagement of said fingers with the paper and means varying the relative peripheral speed of said fingers and the plate while said gripping portions are in engagement therewith. 65
- 70 6. A delivery mechanism for printing machines, embodying therein a rotatable member having a plurality of gripping areas thereon associated with the plate cylinder, means actuating said member, an oscillatory shaft carried by, and rotatable with, said rotatable member, a plurality of gripper fingers mounted upon said shaft, and co-operating with said gripping areas respectively, said gripper fingers each embodying therein a block carried by, and movable with, said shaft, a gripping portion pivotally mounted in relation to said block, cooperating means carried by said block and said gripping portion respectively, whereby said gripping portion and said block are moved in unison in one direction, a resilient tongue carried by, and projecting forwardly of, said portion, having the end thereof projected toward the plate, and a flexible connection adapted to transmit movement from said block to said portion in the other direction, whereby, with the actuation 75
- 80 85 90 95 100 105 110 115 120 125 130

thereof, each finger will be yieldingly thrust into engagement with the printing plate, means adapted to impart a timely actuation to said shaft to first thrust said gripping portions into engagement with the plate and then into engagement with said gripping areas, and subsequently away from said areas to insure the engagement and disengagement of said fingers with the paper and means varying the relative peripheral speed of said fingers and the plate while said gripping portions are in engagement therewith.

7. A delivery mechanism for printing machines, embodying therein a rotatable member having a plurality of gripping areas thereon associated with the plate cylinder, means actuating said member, an oscillatory shaft carried by, and rotatable with, said rotatable member, a plurality of gripper fingers mounted upon said shaft, and cooperating with said gripping areas respectively, said gripper fingers each embodying therein a block carried by, and movable with, said shaft, having a stop upon one side of said shaft, and a spring seat upon the opposite side thereof, a portion pivotally mounted in relation to said block, having a heel adapted to coöperate with said stop and a spring seat oppositely disposed to the spring seat upon said block, a resilient tongue carried by, and projecting forwardly of, said portion, having the end thereof projecting toward the plate, and a spring mounted between said spring seats, whereby, with the actuation thereof, each finger will be yieldingly thrust into engagement with the printing plate, means adapted to impart a timely actuation to said shaft to first thrust said gripping portions into engagement with the plate and then into engagement with said gripping areas, and subsequently away from said areas to insure the engagement and disengagement of said fingers with the paper and means varying the relative peripheral speed of said fingers and the plate while said gripping portions are in engagement therewith.

8. A delivery mechanism for printing machines, embodying therein a rotatable member having a plurality of gripping areas thereon associated with the plate cylinder, a plurality of gripper fingers coöoperating with said gripping areas respectively, said gripper fingers each embodying therein means whereby, with the actuation thereof, each finger will be yieldingly thrust into engagement with the printing plate, means adapted to impart a timely and simultaneous actuation to said fingers to first thrust said fingers into engagement with the plate and then into engagement with said gripping areas, and subsequently away from said gripping areas to insure the engagement and disengagement thereof with the paper, and a mechanism for imparting variable

speed of rotation to said rotatable member, embodying therein a gear rotating at constant speed, in synchronism with the printing couple, connections between said gear and said rotatable member, and a controlling mechanism operative upon said connections, whereby, during each rotation of said member, its speed of rotation will be varied to permit a feeding movement of the paper in relation to said fingers, and will be accelerated to preserve the operative relation of said fingers to said plate, as to the succeeding delivery operation.

9. A delivery mechanism for printing machines, embodying therein a rotatable member having a plurality of gripping areas thereon associated with the plate cylinder, a plurality of gripper fingers coöoperating with said gripping areas respectively, said gripper fingers each embodying therein means whereby, with the actuation thereof, each finger will be yieldingly thrust into engagement with the printing plate, means adapted to impart a timely and simultaneous actuation to said fingers to first thrust said fingers into engagement with the plate and then into engagement with said gripping areas, and subsequently away from said gripping areas to insure the engagement and disengagement thereof with the paper, and a mechanism for imparting variable speed of rotation to said rotatable member, embodying therein a gear rotating at constant speed, in synchronism with the printing couple, a bell crank lever pivotally mounted upon, and rotatable with, said gear, a crank upon said rotatable member, a link connection between one arm of said lever and said crank, and a non-rotatable cam operative upon the other arm of said lever, said cam having a rise and a fall thereon, with the portions thereof between said rise and said fall, concentric with the axis of said rotatable member, whereby, during each rotation of said member, the speed of rotation will be varied to permit a feeding movement of the paper in relation to said fingers, and will be accelerated to preserve the operative relation of said fingers to said plate, as to the succeeding delivery operation.

10. A delivery mechanism for printing machines, embodying therein a rotatable member having a plurality of gripping areas thereon associated with the plate cylinder, a plurality of gripper fingers coöoperating with said gripping areas respectively, means adapted to impart a timely and simultaneous actuation to said fingers to bring them into engagement with the printing plate and then into engagement with said gripping areas, and subsequently away from said areas to insure their engagement and disengagement with the paper, means operating in synchronism with the printing couple, operative connections between said means

and said rotatable member, and a controlling mechanism operative upon said connections to vary the speed of rotation of said rotatable member while said finger is in engagement with the plate, to thereafter impart a feeding movement to the sheet coincident with the speed of the printing couple, and after the said grippers have released the sheet, to accelerate the speed of said 10 rotatable member to compensate for the variance in speed while the grippers are in engagement with the plate.

11. A delivery mechanism for printing machines, embodying therein a rotatable member having a plurality of gripping areas thereon associated with the plate cylinder, a plurality of gripper fingers coöperating with said gripping areas respectively, means adapted to impart a timely and simultaneous 15 actuation to said fingers to bring them into engagement with the printing plate and then into engagement with said gripping areas, and subsequently away from said areas to insure their engagement and disengagement with the paper, means operating 20 in synchronism with the printing couple, positive, non-flexible, pivotal connections between said last named means and said rotatable member, and a controlling mechanism operative upon said connections, whereby, during each rotation of said member, its speed of rotation will be varied to 25 permit a feeding movement of the paper in relation to said fingers, and will be accelerated to preserve the operative relation of said fingers to said plate, as to the succeeding delivery operation.

12. A delivery mechanism for printing machines, embodying therein a rotatable

member having a plurality of gripping areas 40 thereon associated with the plate cylinder, a plurality of gripper fingers coöperating with said gripping areas respectively, means adapted to impart a timely and simultaneous actuation to said fingers to bring them into 45 engagement with the printing plate and then into engagement with said gripping areas, and subsequently away from said areas to insure their engagement and disengagement with the paper, and a mechanism for imparting 50 variable speed of rotation to said rotatable member, embodying therein a gear rotating at constant speed, in synchronism with the printing couple, a bell crank lever pivotally mounted upon, and rotatable with, 55 said gear, a crank upon said rotatable member, a link connection between one arm of said lever and said crank, and a non-rotatable cam operative upon the other arm of said lever, said cam having a rise and a 60 fall thereon, with the portions thereof between said rise and said fall, concentric with the axis of said rotatable member, whereby, during each rotation of said member, the speed of rotation will be varied to permit a 65 feeding movement of the paper in relation to said fingers, and will be accelerated to preserve the operative relation of said fingers to said plate, as to the succeeding delivery operation.

70
In witness whereof I have hereunto affixed my signature this 18th day of July, 1918, in the presence of two subscribing witnesses.
